DESIGN FOR A HORSE-TRAILER BODY

Charles J. Shields, San Jose, Calif.

Application November 16, 1937, Serial No. 72,937

Term of patent 14 years

To all whom it may concern:

Be it known that I, Charles J. Shields, a citizen of the United States, residing at San Jose, in the county of Santa Clara and State of California, have invented a new, original, and ornamental Design for a Horse-Trailor Body, of which the following is a specification, reference being had to the accompanying drawing, forming a part thereof.

Figure 1 is a side view of a horse-trailor body, showing my new design;

Figure 2 is another side view of the same;
Figure 3 is a front elevation of the same;
Figure 4 is a rear elevation of the same;
Figure 5 is a top plan view of the same.

I claim:

The ornamental design for a horse-trailor body, as shown.

CHARLES J. SHIELDS.
